United States Patent Office.

WALKER OLDS, OF ALBANY, ILLINOIS.

Letters Patent No. 92,636, dated July 13, 1869.

IMPROVED BRICK-MACHINE.

The Schedule referred to in these Letters Patent and making part of the same.

To all whom it may concern:

Be it known that I, WALKER OLDS, of Albany, in the county of Whitesides, and State of Illinois, have invented a new and useful Improvement in Brick-Machines; and I do hereby declare that the following is a full, clear, and exact description of the same, reference being had to the annexed drawings making part of this specification, in which—

Figure 1 is a top view.

Figure 2 is a bottom view.

Figure 3 is an elevation.

Figure 4 is a vertical central section.

Figure 5 is a perspective view of the mechanism connected with part of the press.

Figure 6 is a perspective view of the brick-moulds.

Figures 7, 8, 9, and 10 are views of parts of the machine, to be particularly hereinafter described.

The same letters in all the figures are used to indicate identical parts.

My improvements relate to machines for pressing brick, and their character will fully appear from the following specification, and the claim thereto annexed.

The machine is supported upon a strong frame adapted to the mechanism. This frame is composed of sill-pieces A, and transverse beams A¹, vertical posts A², and upper frame-work A³.

At A⁴ there are vertical iron rods, passing entirely through the frame, with nuts, by which the whole frame is tightly bound together.

A horizontal frame-work, at A⁵, supports the floor of the pug-mill and the greater portion of the operating-mechanism, and A⁶ is the bridge-tree, on which is placed the step for the toe of the main driving-shaft B.

The power may be applied to the upper end of the main shaft by a beam, B', when horses are used, or by means of a band and pulley, or a system of gearing, when other kinds of power are to be applied.

The pug-mill is within the frame, and the clay is tempered by means of arms attached to the shaft B, which, being of ordinary construction, are not shown.

The sweeps C, attached to the shaft immediately above the floor of the pug-mill, are used for the purpose of sweeping the tempered clay outwards, and towards the presses.

Below the pug-mill an arm, D, with a segment of a bevel-wheel attached, is fastened to the main shaft B, with the revolution of which its cogs alternately engage similar bevel-segments, attached to arms adjustably fastened to the horizontal shaft E', so that an oscillating revolution is given to said shaft, as the cogs of the segment D alternately engage those of the segments E E, moving the shaft as far as their cogs engage. These arms are adjustably attached, so that as the cogs become worn, the segments may be kept in gear by moving the segments E nearer to the shaft B.

On the outer ends of the shaft E' are placed seg-

ments of spur-wheels, F, each being about a quadrant in form.

The teeth of the spur-segments F engage racks G' on the base of the metallic moulds G, so that as the segments F oscillate from side to side, they shall throw the moulds G from side to side of the machine. These moulds are two-thirds of the length of the frame, so that as the moulds are thrown from side to side, one-half the brick-moulds shall be opposite to the press to be filled with clay, and the others opposite plungers arranged on each side of the press, which will force out the bricks contained in the moulds; so that while half the moulds are being filled, the other half are being delivered of the bricks.

The pressing-mechanism is constructed and arranged as follows:

H is a bevel-wheel on the upper end of the main shaft, and driving two bevel-pinions, I I, which give revolution to the cranks I¹.

The pitman I² is attached to the crank-pin above, and below to the vertical pressing-head K, which moves up and down in ways.

These heads, K, being raised into the pug-mill, the clay is forced under them by the sweeps C, and as they descend they force the clay down in front of the horizontal press-heads N.

The vertical press-head K has two arms, K², extending upwards, as shown in fig. 3.

Slots are cut in these arms, to receive the ends of the oscillating levers L, which are centrally pivoted to the frame, and connected, by the pitman L¹, to the knife L².

This knife has thus a reciprocating motion, the reverse of that of the press-head K, and is used to cut the clay immediately behind the moulds, after they have been filled by the press. These parts are duplicated, there being a press on each end of the machine.

The rods L and L¹ are connected by a wooden pin, L³, which forms their pivot, so that if a knife should encounter a stone, the wooden pivots would break, and thus prevent more serious injury to the machine.

The horizontal press-heads are simultaneously operated by the cam M, attached to the shaft B.

The cam presses against friction-rollers, M², attached to the press-heads N, above the iron plates N', which are rigidly attached to the press-heads.

In order to counteract the lateral pressure of the cams against the press-heads, beams O are attached thereto, (see fig. 2,) lying along the sides of the transverse beams of the press.

Arms O¹ are attached by round bolts to the beams O, and these arms have a rounded recess near the ends, to receive the wrist-pin M¹, projecting from the face of the cam. As the cam revolves, these wrist-pins come in contact with the edges of the arms O¹, which are pressed against the wrist-pins by the springs O²,

until the wrist-pins enter the notches, when the cam, acting upon the arms O^1 , will draw back the beams O , and the press-heads N . When they have been drawn back, the pins are disengaged from the notches by means of the adjustable bosses M^2 , which will bear against the ends of the arms. These bosses are adjustably attached to the cam by set-screws passing through slots in the bosses, so that they may be readjusted as they become worn from use.

Connected with the press-heads N , which operate on the clay forcing it into the moulds, and arranged on each side of the latter, is a corresponding number of heads, N^2 , which, moving simultaneously with the press-heads, force the bricks from the moulds which have been first filled, and are then shifted to the sides of the machine, alternately.

Air-holes, shown in figs. 3 and 4, are formed in the heads N^2 . The ends of these heads should be covered with a woven fabric to prevent adhesion.

Slots are cut in the vertical posts A^2 A^2 opposite the ends of the moulds, as shown in fig. 3, in order to permit the clay carried on the ends to escape.

Set-screws, G^2 , are passed through these posts, to form stops to regulate the throw of the moulds, as the sharp points of these screws will not catch the clay adhering to the ends of the moulds, as would be the case if broad surfaces were employed for this purpose.

The horizontal presses may be made either against a press-plate, P' , held in position by a beam, P , secured to the frame, or reciprocating plungers may be used to act from the outside against the brick in the mould, simultaneously with the pressure of the horizontal press-heads from within.

The heads Q are attached by lugs to the oscillating shaft Q^1 , from which arms Q^2 extend downwards, which are fastened by a rod, Q^3 , to the reciprocating rods Q^4 , fastened to and moving with the press.

The rod Q^3 passes through slots in the ends of the rods Q^4 , and set-screws, passing through the ends of the rods Q^4 , and bearing against the rod Q^3 , are used to regulate the extent of reciprocating motion to be given to the plungers Q .

R R are sliding boards, moving freely in vertical grooves in the frame-timbers, and supported on points R^1 . These points have a reciprocating motion, derived from the oscillating arms R^2 , (figs. 7 and 8,) which are centrally pivoted and acted upon by slots in the heads N^2 , so that as the heads move forward to press the bricks out of the moulds, the points R^1 will be retracted, thus disengaging the lower board R , which will fall behind the brick as soon as the heads N^2 are drawn back, and the points will be again projected as the heads retire, so as to support the other boards R . These boards being placed, as they fall, behind the bricks, as they are forced from the moulds, serve to

separate the bricks successively forced from the mould, and to carry them forward, by the action of the press, on to the revolving apron on which they are to be removed.

These boards may also be used to carry the bricks to be haked in the yard, and when returned are inserted at the top of the frame.

S is an apron to receive the bricks as they are pressed from the machine. It may be mounted on a frame supported upon wheels, so that the bricks may be wheeled away on the apron.

A thin sheet of metal should be placed on the sill in front of the heads N^2 , to form a bridge connecting the moulds with the apron S .

What I claim as my invention, and desire to secure by Letters Patent, is—

1. The combination of the pug-mill shaft B , segmental head D , and adjustable segmental heads E E , for giving an oscillating rotation to the shaft E' , substantially as and for the purpose set forth.

2. The reciprocating moulds G , in combination with the oscillating segments F , and plungers N and N^2 , substantially as described.

3. In combination with the press-heads K , and arms K^2 , the lever L , rods L^1 , and knife L^2 , substantially as set forth.

4. In combination with the knife L^2 , rods L^1 , and lever L , the wooden pins L^3 , substantially as and for the purpose set forth.

5. In combination with the shaft B and press-heads N , the cam M , beams O , arms O^1 , springs O^2 , and wrist-pins M^1 , and bosses M^2 , substantially as set forth.

6. In combination with the reciprocating moulds G , the slotted vertical posts A^2 , and set-screw G^2 , substantially as described.

7. The combination of the reciprocating moulds G , and press-heads N , and plungers N^2 , arranged to operate substantially as set forth.

8. The reciprocating moulds G , when so arranged as to receive the clay in the centre of the machine, and to discharge the bricks alternately on each side of the press, as set forth.

9. The combination of the press-heads N and Q , and parts Q^1 , Q^2 , Q^3 , and Q^4 , substantially as herein set forth.

10. In combination with the reciprocating moulds G , and plungers N^2 , the boards R , reciprocating points R^1 , and oscillating arms R^2 , substantially as set forth.

In testimony whereof, I have signed my name to this specification in the presence of two subscribing witnesses.

WALKER OLDS.
